UNITED STATES PATENT OFFICE.

JAMES M. TRIGGS, OF HUNTINGTON, INDIANA, ASSIGNOR TO THE MAJESTIC COMPANY,
OF HUNTINGTON, INDIANA, A CORPORATION OF INDIANA.

DESIGN FOR A DUPLEX REGISTER.

52,086.

Specification for Design.

Patented June 4, 1918.

Application filed March 22, 1918. Serial No. 224,083. Term of patent 7 years.

To all whom it may concern:

Be it known that I, JAMES M. TRIGGS, a citizen of the United States, residing at Huntington, in the county of Huntington and State of Indiana, have invented a new, original, and ornamental Design for a Duplex Register, of which the following is a specification, reference being had to the accompanying drawing, forming a part thereof.

The figure is a perspective view of a duplex register showing my new design.

I claim:

The ornamental design for a duplex register, substantially as shown.

JAMES M. TRIGGS.
